GRILLE

Edward L. Anderson, Grosse Ile, Mich., assignor
to American Blower Corporation, Detroit,
Mich., a corporation of Delaware

Application December 26, 1934, Serial No. 759,176

18 Claims. (Cl. 98—101)

This invention relates to systems for introducing air into one space from another, and more particularly to outlet grilles or registers for such systems.

5 One of the objects of the invention is to provide a new and improved grille or register for the discharge opening of ventilating or heating systems, such as the opening in a wall of a room, and to provide a grille for this purpose having improved air distributing characteristics.

10 Another object of the invention is to provide a grille for the discharge opening of ventilating or heating systems and to provide a grille for this purpose having a new and improved arrangement 15 of parts for improving diffusion and distribution of air discharged therethrough.

Another object of the invention is to provide a new and improved grille for the discharge opening into a room of heating or ventilating systems and one which induces rapid intermingling of 20 room air with incoming air to quickly balance the difference in temperature between the same.

Another object of the invention is to provide a grille for the outlet opening of ventilating 25 systems into a room, and to provide a grille for this purpose so constructed as to cause the velocity of the air passing therethrough to be increased, to obtain good circulation and distribution of air throughout the room and for doing 30 so in a manner such that the presence of drafts or cold zones is not apparent to persons in the room.

Another object of the invention is to provide a new and improved grille having a plurality of 35 passageways for air and to provide a grille of this character in which the size of the passageways may be readily varied to control the volume of air passing therethrough and to also vary its direction of flow.

40 A further object of the invention is to provide a grille of the above mentioned character having improved air diffusing and distributing characteristics yet one which is simple in construction and economical to manufacture.

45 The invention consists in the improved construction and combination of parts, to be more fully described hereinafter and the novelty of which will be particularly pointed out and distinctly claimed.

50 In the accompanying drawings, to be taken as a part of this specification, I have fully and clearly illustrated a preferred embodiment of my invention, in which drawings—

Figure 1 is a front view shown in elevation 55 of my improved grille;

Fig. 2 is a view shown in cross section taken along the line 2—2 of Fig. 1;

Fig. 3 is a view of a part of the grille shown disassembled to show how it is formed;

Fig. 4 is a front view of a grille and damper 5 therefor embodying features of my invention;

Fig. 5 is a view shown in cross section taken along the line 5—5 of Fig. 4;

Fig. 6 is a fragmentary cross sectional view of 10 the grille showing the damper in different positions;

Fig. 7 is a view similar to Fig. 5 showing one of the positions in which the damper may be arranged;

Fig. 8 is a plan view shown in cross section of 15 a grille having two dampers and positions in which they may be arranged to direct the air;

Fig. 9 is a view similar to Fig. 8, of a grille shown in cross section with the dampers in still 20 another position;

Fig. 10 is an end view in cross section taken along the line 10—10 of Fig. 9;

Fig. 11 is a side view shown in cross section 25 taken along the line 11—11 of Fig. 5;

Fig. 12 is an enlarged view shown partly in elevation and partly in cross section of parts of the damper operating means, and

Fig. 13 is an enlarged view shown partly in elevation and partly in cross section taken in the direction of the arrows 13—13 of Fig. 11. 30

Referring to the drawings and more particularly to Figs. 1, 2 and 3, there is shown an air outlet grille or register for the directing and diffusing of air discharged therethrough, the grille shown being of a type suitable for mounting in the wall of a room and for use either with heating or air conditioning systems. This grille comprises a frame 1 and a plurality of spaced vanes 2, arranged behind the frame to provide 35 passageways 3 for air. In order to provide a grille by means of which the air discharged therethrough into a room is efficiently diffused and mixed with the room air, and in a manner so that no cold zones or drafts are apparent, the passageways 3 are spaced and the face of the grille 40 closed between the outlets 4 of adjacent passageways. Thus, when air is discharged through the passageways 3 of the grille, areas of relatively low pressure are produced between adjacent streams of air, due to the velocity of the air, and into these areas of reduced pressure, the air of the room flows and is rapidly intermingled with the incoming air thus inducing circulation of air throughout the entire room. I obtained this desirable result with an economically constructed 45

50

55

grille, the construction including the use of a plurality of sheet metal channel-shaped members arranged in spaced relation behind the frame 1 with the connecting sides 5 of the channel-shaped members toward the face of the frame, the rearwardly extending sides constituting the vanes 2.

Thus the channel-shaped members may be readily formed and arranged in spaced relation 10 behind the frame 1 so that adjacent vanes or sides 2 of adjacent channel-shaped members cooperate to form a plurality of spaced passageways 3. Also the sides 5, of the channel-shaped members, serve to provide closed spaces on the 15 face of the grille against which room air is drawn. Air that is out of range of the force of the air streams flows to the areas of low pressure maintained by the velocity of the air streams and, as shown in Fig. 11, enters the zones 20 of low pressure at both the top and bottom of the frame. The air thus flowing in at the top and bottom of the frame impinges against the closed wall faces 5 and is diverted downwardly, the upper and lower streams of air intermingling 25 with each other and with the incoming air streams on each side. Each of the channel-shaped members is provided on the faces 5 with an indented portion 5^a providing a plurality of channels or pockets on the face of the grille in 30 which the air pressure is reduced and as a result into which currents of room air are induced to flow.

Preferably, the frame is constructed of sheet metal having sides 6, 7, 8 and 9 forming a body 35 for insertion in an opening in a wall and having outwardly extending flanges 10, 11, 12 and 13 which cooperate to form what may be termed the face of the frame. Edge portions of the sides 6, 7, 8 and 9 are first bent inwardly and 40 then outwardly to form an abutment or rearwardly facing shoulder 14 around the inside of the frame, the edge 15 of which defines the opening 16 of the frame. The channel-shaped members extend from side 10 to side 11 seating 45 against the shoulder 14 and may be welded or otherwise suitably fixed thereto.

When grilles are employed as the discharge opening into a room of a ventilating system, they are usually located in a wall and near the 50 ceiling of the room in order to obtain as good distribution of the cold air as possible throughout the room. The reason for this, of course, is that the colder and consequently heavier air discharged into the room soon descends after leaving the grille, resulting not only in unsatisfactory distribution of the cold air throughout the room but also resulting in drafts or cold zones uncomfortable to persons who may be beneath the grille. In order to provide a grille for the 55 discharge opening of ventilating systems and one by reason of which cold air is well distributed throughout a room without apparent cold zones, I provide the passageways 3 tapered, tapering from relatively large inlets 20 to relatively small outlets 4. As air flows through the passageways 3 its speed is increased by reason of the tapered sides 2 which result in its being projected farther into the room than would be the case if 60 discharged through passageways formed by parallel sides. It will now be seen that not only is good distribution of the air through the room obtained, by projecting it farther thereinto, but the relatively high velocity of the air at the outlets 4 produces a relatively low area of reduced pressure at the face of the grille and in 65

the indented portions 5^a. Also, it will be seen that the air passing through the tapered passageways 3 is crowded or compressed so that slightly beyond the face of the grille it tends to expand in all directions and consequently tends to rapidly intermingle with the room air.

To obtain tapered passageways, the sides or vanes 2 are angularly disposed relative to sides 5 so that adjacent sides of adjacent channel-shaped members cooperate to form the spaced 10 passageways 3. To discharge air over a greater area, the passageways 3 extend at an angle to the face of the frame, and vary in degree of angularity each side of the center channel-shaped member 24. As shown in Fig. 2, the center channel-shaped member 24 has its sides or vanes 2 converging rearwardly. The sides 2 of the channel-shaped members, either side of the center member, have one side bent at substantially 15 an obtuse angle with side 5 and the other at substantially an oblique angle with side 5, as shown in Fig. 3, and the degree of angularity of the sides of successive channel-shaped members vary so that when assembled they cooperate to form a plurality of tapered angularly extending passageways for air, which passageways vary in degree of angularity, either side of the center of the frame. At the sides 8 and 9 of the frame, a half of a channel-shaped member may be utilized as shown. The rear ends of the vanes 2 may be curled outwardly, as at 22, to provide a 20 larger inlet for inducing the flow of air thereinto.

Referring now to Figs. 5 to 11, there is shown a grille having a frame 30 similar to the frame 1, of the grille heretofore described. Behind the frame 30 is arranged a plurality of triangular shaped members 32 with sides 33 arranged toward the front of the grille and sides 34 extending to an apex toward the rear of the frame. The triangular shaped members 32 are arranged in spaced relation so that sides 34 cooperate with adjacent sides of adjacent members 32 to form a plurality of tapered passageways 36 tapering from relatively large inlets defined by the apexes 40 of adjacent members 32 to relatively small outlets 38. The sides 33 of the triangular shaped members serve to close the spaces between the outlets 38 and, as previously described in connection with the grille of Figs. 1 and 2, a space of 45 reduced pressure is produced along the outer face of sides 33 between projected streams of air into which room air flows, thus causing a 50 circulating of air throughout the room toward the grille. As in the previously described grille, indented portions 33^a are provided in the sides 33 forming offset spaces slightly back of the 55 discharge openings 38 in which a substantial lowering of the pressure is caused and maintained by the velocity of the air streams on each side. It will be understood that the members 32 need not necessarily be triangular in shape as it will be seen that they could be angle-shaped, omitting sides 33 if desired, and still 60 cooperate to provide a plurality of tapered passageways, between which room air would flow to the spaces therebetween at the face of the grille.

A second series of angle-shaped members 40 is arranged behind members 32 and staggered in relation thereto so that sides 41 cooperate 70 with adjacent sides 34 of members 32 to form a plurality of angularly extending passageways 43 in communication with outlets 38. The members 40 are relatively spaced across the width of the frame providing openings 45 between adja- 75

cent members at the rear of the frame for the entrance of air. The rear ends of sides 41 may be curled relatively outwardly, as at 48, to induce flow of air into the openings 45. In the present showing, sides 41 of each member 40 are connected by a third side 50. However if desired, this side 50 may be omitted and the sides 41 extend to an apex toward the front of the frame. Nor need the sides 41 of members 40, nor the 10 sides 34 of members 32 necessarily be connected, for a plurality of spaced alternately angularly disposed vanes may be arranged to provide the passageways. In any event, it is desirable that the sides 34 and sides 41 be relatively angularly disposed so that they cooperate to form a plurality of angularly extending tapered passageways 43, tapering from relatively large inlets in communication with openings 45 to relatively small outlets 20 communicating with outlets 38 in order to increase the velocity of air passing therethrough.

Referring more particularly to Fig. 11, the members 40 are welded or otherwise suitably secured at both ends to movably supported top and bottom cross members 52 and 53 so that they 25 may be moved as a damper to vary the size of the passageways 43. The inner edges of the cross members 52 and 53 are provided with a plurality of angle-shaped cut-outs 44 to conform to the shape of the members 40 and also for 30 clearing the apexes of the triangular-shaped members 32. In the grille shown in Fig. 5, the damper is mounted at each end on a shaft or rod 55 which in turn is pivotably and slidably supported by a bracket 56. Connecting rods 58 35 are provided, one at each end of the damper and extend between the cross members 52 and 53 with its ends extending into apertured brackets 59 which are welded or otherwise suitably fixed to the cross members. The rods 55 extend 40 through the openings 38 and through aligned apertures in the end members 40 and vertical rods 58, the ends being threaded to receive locking nuts 60. The ends of the rods 55 are formed 45 with a reduced portion 62 providing a shoulder 63, and between this shoulder 63 and the nuts 60 the members 40 and rods 58 are tightly clamped.

Preferably the brackets 56 are fixed to the members 32 intermediate the ends thereof such 50 as by screws 65. The brackets are each formed having a semi-circular portion in which is provided a slot 66, Fig. 13, through which the rods 55 extend and which permit pivotal movement 55 of the rods therein. The brackets 56 are provided with seats for the pivot members 66, the seats being formed in the present instance by a bore and a counterbore forming the edge 67 on which the tapered portion 68 of the pivot seats. The reduced portions 69 of the pivots 66 are 60 threaded to receive the nuts 70. The rods 55 extend slidably through apertures 71 in the pivotal members 66 and are provided with knobs or handles 72. Air may be delivered under pressure 65 to the rear of the grille through shaft or stack 73, as shown in Fig. 11, and discharged through the grille into the room. The damper may be moved laterally or toward or away from the members 32 to vary the size of the passageways 43 to regulate the volume of incoming air and to direct the air in different directions.

In Fig. 6, two positions of the damper are shown. In full lines, the rods 55 have been pushed in, carrying the damper to the rear and 70 away from the members 32, and has also been

pivoted, carrying the damper to the right as seen on the drawings. In this position, the sizes of alternate passageways 43 have been increased 5 permitting more air to flow therethrough while the other passageways effected by such movement have been reduced in size. By pivoting the rod 55 to neutral position and pulling it outwardly, the damper is moved to close the openings 38 as shown in dotted lines.

In Figs. 7, 8 and 9, there are shown other arrangements of dampers. For example, in Fig. 7, the damper has been moved to the extreme left, thus closing those passageways which extend toward the right and enlarging the other passageways so that all of the air is directed to the left as seen on the drawings. In Fig. 8, there is shown a grille having two independently movable dampers arranged so that some of the air is directed to the right and some to the left. In Fig. 9 is shown the grille of Fig. 8 having the two dampers arranged in still a different manner. In this arrangement the adjacent ends of the dampers at the center of the grille have been moved rearwardly and the other ends forwardly. This results in the passageways 38^a being relatively larger than the others and successive passageways vary in size from the center of the grille to the ends. It will also be seen that the damper can be adjusted so that the passageways are either tapered or uniform in size, as for example the passageways 38^b which in this arrangement of the damper are not tapered, and furthermore that the degree of taper of the passageways can be varied as desired.

From the foregoing description, it will now be seen that I have provided a new and improved grille for diffusing and directing air and one having improved air distributing and circulating characteristics. This improved distribution is accomplished by a grille through which the velocity of the air is increased, resulting in its being discharged to a greater distance into a room than is attainable by ordinary grilles. In addition I have provided a grille so constructed that areas of reduced pressure are produced at 40 the face thereof, caused by the velocity of adjacent streams of air, into which areas the room air flows and is readily intermingled with the incoming air. This facilitates the mixing of the incoming air with that already in the room so that the time required for the balancing of the 45 temperatures of the room air and incoming air is materially reduced.

What I claim and desire to secure by Letters Patent of the United States is:

1. A grille comprising a frame, and a plurality of relatively spaced vanes arranged back of said frame, said vanes being relatively arranged to cooperate in forming a plurality of passageways for air, the vanes forming the passageways having their rear edges bent relatively outward and rounded to induce crowding of air into said passageways to increase the effective flow capacity of said passageways.

2. A grille comprising a frame, and a plurality of vanes arranged behind the frame, some of said vanes being angularly disposed relative to adjacent vanes and to the face of the frame and cooperating with said adjacent vanes to form a plurality of tapered passageways, tapering from relatively large inlets to relatively small outlets for increasing the velocity of air passing therethrough, the vanes forming said passageways having their rear edges bent relatively outward and rounded to induce crowding of air into said passageways.

sageways to increase the effective flow capacity of said passageways.

3. A grille comprising a frame, and a plurality of channel-shaped members arranged behind the frame with the connecting sides thereof disposed toward the face of the frame and with the other sides extending rearwardly thereof, said channel-shaped members being arranged in spaced relation with the adjacent rearwardly extending sides 10
10 of adjacent members cooperating to form a plurality of passageways for air, said channel-shaped members having rearwardly bent portions in the connecting sides thereof providing relieved spaces wherein air is induced to flow and rapidly inter-
15 mingle with the discharging air due to the low pressure area maintained in said spaces by the velocity of the stream of discharging air.

4. A grille comprising a frame, and a plurality of relatively spaced channel-shaped members behind the frame with the connecting sides of said members toward the face of the frame and the other sides extending rearwardly thereof, adjacent rearwardly extending sides of adjacent members being angularly disposed relative to the face 20
25 of the frame in planes diverging from the front to the rear thereof, and with the sides of said members relatively varying in degree of angularity whereby they cooperate to form a plurality of spaced tapered passageways angularly extending
30 and relatively varying in degree of angularity.

5. A grille comprising a frame, and a plurality of angle-shaped members arranged behind the frame with their apexes toward the rear thereof, said members being arranged in spaced relation 35
35 with adjacent sides of adjacent members cooperating to form a series of spaced tapered passageways, tapering from relatively large inlets at the rear of the frame to relatively small outlets at the front of the frame, and a second plurality of angle-shaped members relatively arranged in 40
40 staggered spaced relation between the first-named members and with their apexes disposed toward said outlets, the angle between opposite sides of said second-named members being less than the angle formed between the adjacent sides of adjacent members of said first-named members 45
45 whereby to divide each of said tapered passageways into two angularly extending tapered passageways.

6. A grille comprising a frame, a plurality of angle-shaped members arranged in relatively spaced relation behind said frame with their apexes toward the rear thereof, and a second plurality of angle-shaped members relatively arranged in 50
55 in staggered spaced relation between the first-named members and spaced therebehind with their sides cooperating with adjacent sides of said first-named angle members to form a plurality of angularly extending passageways for air.

7. A grille comprising a frame, a plurality of angle-shaped members arranged in relatively spaced relation behind said frame with their apexes toward the rear thereof, a second plurality of angle-shaped members relatively arranged in 60
65 staggered spaced relation between the first and spaced therebehind with their sides cooperating with adjacent sides of said first-named angle members to form a plurality of angularly extending passageways for air, the sides forming said 70
70 passageways being in overlapping relation and extending in the same general direction.

8. A grille comprising a frame, a plurality of triangular-shaped members arranged behind the frame with a side of each member toward the face 75
75 of the frame and the other two sides extending

rearwardly to an apex, said members being arranged in spaced relation with the rearwardly extending adjacent sides of adjacent members cooperating to form a plurality of spaced tapered passageways, tapering from relatively large inlets to relatively small outlets, a plurality of angle-shaped members arranged behind said triangular-shaped members one in each of said tapered passageways with their sides converging forwardly and cooperating with sides of said tapered passageways to form a plurality of angularly extending tapered passageways for the passage of air, tapering from relatively large inlets to relatively small outlets, movable connecting means for the said angle members, and means for moving said connecting means and said angle members to vary the size of the angularly disposed passageways.

9. A grille comprising a frame, a plurality of alternately angularly disposed vanes arranged behind the frame with openings for air between some of said vanes, a second plurality of alternately angularly disposed vanes arranged behind the first-named vanes with openings for air between some of said vanes, said second plurality of vanes being staggered relatively to the first cooperating therewith to form a plurality of spaced angularly extending passageways, movable connecting means for said second-named plurality of vanes, and a slidably supported pivotable member for moving said connecting means and said second-named vanes whereby the size of the angularly disposed passageways may be varied.

10. A grille comprising a frame, a plurality of angularly disposed vanes arranged behind the frame, said vanes being relatively spaced, a movable damper arranged behind said vanes and having wall means cooperating therewith to form a plurality of passageways for air, the capacities of said passageways being variable by said damper, said damper having inlet openings therein opening into said passageways, said inlet openings being defined by portions of said wall means with the said portions being bent outwardly and rounded to induce crowding of the air through said inlets to thereby increase the effective flow capacity of said inlets.

11. A grille comprising a frame, wall means arranged behind the frame providing a plurality of spaced outlets for air, a movable damper arranged behind said wall means and having wall means cooperative with said first-named wall means in overlapping relation thereto to provide a plurality of tapered passageways for air, tapering from relatively large inlets to relatively small outlets with their longitudinal axes angularly extending relative to the face of said frame, and means for moving said damper to vary the size of said passageways.

12. A grille comprising a frame, a plurality of vanes arranged behind said frame and angularly disposed relative to the face of the frame with successive vanes alternating in direction of extension, some of said vanes defining outlet openings for air, a plurality of channel-shaped members spaced back of said vanes in staggered spaced relation thereto, said channel-shaped members having a wall disposed toward and overlying said outlet openings and having sides extending rearwardly therefrom, the sides of each channel-shaped member extending at angles relative to said wall and outwardly from each other, the said sides cooperating with said vanes to provide a plurality of angularly extending passageways successively alternating in direc- 70
75
80
85
90
95

tion of extension and opening into said outlets, the adjacent rear edges of adjacent channel-shaped members cooperating to provide inlet openings to said passageways.

- 5 13. A grille comprising a frame, a plurality of vanes arranged behind said frame and angularly disposed relative to the face of the frame with successive vanes alternating in direction of extension, some of said vanes defining outlet openings for air, a plurality of channel-shaped members spaced back of said vanes in staggered spaced relation thereto, said channel-shaped members having a wall disposed toward and overlying said outlet openings and having sides 10 extending rearwardly therefrom, the sides of each channel-shaped member extending at angles relative to said wall and outwardly from each other, the said sides cooperating with said vanes to provide a plurality of angularly extending passageways successively alternating in direction of extension and opening into said outlets, the adjacent rear edges of adjacent channel-shaped members 15 cooperating to provide inlet openings to said passageways, said rear edges defining said inlets being relatively outwardly bent and rounded to induce crowding of air through said openings to thereby increase the effective capacities of said openings.
14. A fluid discharge device comprising a pair 20 of wall members converging in the direction of fluid flow and spaced to provide an outlet, a member positioned on the inlet side of said wall members and having side walls converging in the direction of fluid flow, the opposed wall surfaces 25 of said side walls and said wall members cooperating to provide flow passageways meeting at said outlet, the side wall and the wall member of each passageway converging in the direction of fluid flow.
- 40 15. A fluid discharge device comprising a pair of wall members converging in the direction of fluid flow and spaced to provide an outlet, a member positioned on the inlet side of said wall

members and having side walls converging in the direction of fluid flow, the opposed wall surfaces of said side walls and said wall members cooperating to provide flow passageways meeting at said outlet, the side wall and the wall member of each passageway converging in the direction of fluid flow, and means operable for moving said member relative to said pair of wall members to vary the flow areas of said passageways.

10 16. A register having a plurality of parallel spaced apart fixed deflectors of generally triangular shape with their front walls generally parallel to the plane of the register, and movable baffle members respectively interposed between said deflectors and having their opposite side walls inclined correspondingly to the opposed walls of the deflector, each of said baffle members having a front wall generally parallel to the plane of the register, and means for simultaneously adjusting said baffle members with respect to said deflectors.

15 17. A grille comprising a plurality of relatively spaced vanes cooperating to provide a plurality of air flow passageways having inlets and outlets, said inlets being defined by edge portions of the vanes with the said edge portions forming each inlet being bent outwardly relative to each other and rounded to induce crowding of air into the flow 20 passageways.

25 18. A grille comprising a frame, a plurality of relatively spaced channel-shaped members disposed behind said frame with the side walls of said channel-shaped members extending rearwardly, adjacent side walls of adjacent channel-shaped members cooperating to provide air flow 30 passageways having inlets and outlets with rear portions of the side walls defining the inlets and being bent outwardly relative to each other and rounded to induce crowding of air into the flow 35 passageways.

EDWARD L. ANDERSON.
